UNITED STATES PATENT OFFICE.

MARTIN A. GREEN, OF ALTOONA, PENNSYLVANIA.

RAILROAD-SWITCH.

SPECIFICATION forming part of Letters Patent No. 269,048, dated December 12, 1882.

Application filed July 17, 1882. (No model.)

To all whom it may concern:

Be it known that I, MARTIN A. GREEN, of Altoona, in the county of Blair and State of Pennsylvania, have invented a new and Improved Railroad-Switch, of which the following is a full, clear, and exact description.

My improvement in railroad-switches consists of an arrangement, substantially as hereinafter described and claimed, whereby the switch-rails carry the wheels over the main rails in such a manner that the main-track rails remain solid and the point and frog are dispensed with; and it also consists of a switch of such arrangement contrived in a manner that a train running along the main line will automatically shift and pass the switch when running in one direction in case the switch is open, and, also, so that a train running from the branch onto the main line will shift the switch automatically, in case it is set for the siding, so as to allow the train to pass onto the main line, all as hereinafter fully described.

Reference is to be had to the accompanying drawings, forming part of this specification, in which similar letters of reference indicate corresponding parts in both the figures.

Figure 1 is a plan view of my improved switch when open, and Fig. 2 is a plan of the same when set for the main line.

The rails *a* represent the main line, which is to be unbroken or uncut, both the frog and the switch-point being dispensed with. *b* represents the inside switch-rail, which is to be of the usual form, turning on the joint *c*.

d is an outside switch-rail, that takes the place of the point and a portion of the stationary outside switch-rail onto which the point turns the wheel. It has a broad flanged top at *e*, and swings on the joint *f*, to lap over the top of main rail *a*, for the wheel to rise on it high enough for the flange to pass over rail *a*, the rail *b* guiding the wheel onto it. Rails *b* and *d* are both connected to the switch-bar *g*, to be worked by the switch-lever *h*, the same as other switches are worked. To carry the wheels of the other side over the rail *a*, I use another switch-rail, *i*, which, together with the stationary sections *j* and *k*, is arranged sufficiently higher than rail *a* to swing over it on ways *l* to make the connections with the sections *j* and *k*, said rail *i* being pivoted at *m*, and

connected to rail *d* by bell-cranks *n* and rods *o*, *p*, and *q*, so that it will swing at the same time that rails *b* and *d* do, and by the lever *h*. The stops *s* are provided to prevent the rail *i* from swinging too far and to prevent it from spreading, and rail *i* is provided with stops *t* *u*, to hook or bear on rail *a* under the pressure of the wheels in such a manner as also to prevent rail *i* from slipping out of place under the wheels. The rail *i* is connected to rod *q* by springs *w*, and the bar *g*, to which rails *b* and *d* are attached, is connected to the lever *h* by a rod, *x*, and a spring, *y*, which are designed, first, to insure the shifting of rails *b*, *d*, and *i* entirely over, to make close joints in case of any slack in the joints of the levers, and, second, to allow sufficient freedom to the switch-rails to enable a train running on the main line toward the left hand of the drawings to automatically shift the rails and pass the switch in case it is open. The springs *w* and *y* are to be set with a little pressure on the rails when in the positions represented in Fig. 1.

I intend to make the spring *w* in two parts, 75 locating the parts on opposite sides of the collar *y'*, and two collars, *a'*, of the rod *q*, for connecting said rod to switch-rail *i*.

For enabling the switch to be more certainly and effectually shifted by the flange of the 80 wheel when passing along the main line, I propose to employ the shifting guard-rail *f'* in connection with switch-rail *i*, and with relation to main rail *a*, as shown, pivoting it alongside of the main rail at *b'* and connecting it to rail *i* by a rod, *c'*, so that when the switch is set for the side track, as in Fig. 1, the rail *f'* will bear near its curved end against the side of the main rail *a*, and the flange of the wheel, wedging in between them, will swing rail *f'* away from the 90 main rail, and will thereby swing rail *i* back from over the main rail, and also shift rails *b* and *d* for the trains to pass unobstructedly, after which springs *w* will force the rail *i* back to its former position. Together with said 95 shifting rail *f'*, I also propose to employ another shifting rail, *e'*, for automatically setting the switch by a train running from the branch onto the main line, so that said train may pass thereon. This rail *e'*, I locate inside of and 100 along the branch rail *k*, pivoting it at *d'*, and connecting it by rod *e'* in such manner that

when the switch is set for the train to pass along the main line, the curved end will bear against the side of rail *k*, to enable the flange of the wheel of the approaching train to wedge it away and swing rail *i*, also rails *b* and *d*, so that the train may pass from the branch onto the main line.

It is obvious that shifting rail *e* may be connected by suitable rods and levers directly with the rail *i*, independently of shifting rail *f*, and I do not limit myself to the connection through said rail, although it is the simplest way.

Having thus fully described my invention, I claim as new and desire to secure by Letters Patent—

1. The combination, with an unbroken rail, *a*, and switch-rail *b*, of the switch-rail *i*, pivoted at *m* and placed higher than rail *a*, the stationary sections *j k*, the ways *l*, the rail *d*, connected with said rail *i* by the mechanism *n o p q*, the stops *s t u*, the springs *w y*, and the rod *x*, as and for the purpose specified.

2. The switch-rails *b d i*, combined and connected with the working-rods *qx* by the springs *w y*, as shown and described.

MARTIN A. GREEN.
